UNITED STATES PATENT OFFICE.

ROCCO C. FAMIGLIETTI AND JOSEPH A. FAMIGLIETTI, OF PROVIDENCE, RHODE ISLAND.

INSPECTION DEVICE.

Application filed January 2, 1925. Serial No. 117.

To all whom it may concern:

Be it known that we, Rocco C. FAMIGLIETTI and Joseph A. FAMIGLIETTI, both citizens of the United States, residing at

5 Providence, in the county of Providence and State of Rhode Island, have invented certain new and useful Improvements in Inspection Devices, of which the following is a specification.

10 Our invention relates to an inspection device adapted for insertion or embodiment in the wall of a house, hotel, or other building.

15 An essential object of our invention is to enable a reading of gas, electric, or other meters from a position outside the building, thus making it unnecessary for the inspector to enter the interior of the building, and in effect excluding the inspector therefrom.

20 Other objects of our invention are security, convenience, and inexpensive construction.

To the above ends primarily our invention consists in such parts and in such combinations of parts as fall within the scope of the appended claims.

25 In the accompanying drawings which form a part of this specification.

Figure 1 is a front elevation of our device mounted in a building wall and in open position,

30 Figure 2, a transverse section of the same on line 2-2 of Figure 1, closed.

Figure 3, an enlarged fragmentary section of the lock taken on line 2-2, and

Figure 4, a rear elevation of our device.

35 Like reference characters indicate like parts throughout the views.

In the drawings 6 represents a building wall, in this instance of brick. As illustrated a sill 7 and a first floor 8 above a cellar 9 are shown, but these may be omitted. In an opening 11 in the wall is fixed an oblong shallow box, or housing represented generally by 12. In detail the box consists of a rectangular frame formed by an upper strip 15, side strips 16 and a strip or base 17 fastened to a board or back 18. The forward edge of the base or strip is in this instance forwardly projected and inclined or beveled to form a weather lip 20. The front of the frame is provided with an internal peripheral recess 21 to receive a door 23 attached by hinges 25 upon its bottom to the base 17. Integral with or attached to the part 17 is a rearwardly directed shelf 27.

50 In this instance the door 23 is supported

in open position by chains or other flexible members 28 whose ends are attached by eye-bolts 29 in the strip 15 and similar bolts 30 in the upper margin of the rear face of the door. The length of these chains are 60 such that the door in open position lies in a substantially horizontal plane. The door may be locked against unauthorized inspection if desired, and in any convenient manner. In the present instance a lock casing 65 33 is fastened to the rear face of the door near its top into which opens a key hole 35. In the casing slides a vertical bolt 37 through an opening 38. The bolt is adapted to enter the hole or cavity 40 of a receiving plate 41 in the strip 15.

The back panel 18 of the box is provided with one or more of sight openings, in this instance four. Two of these 44 are herein shown lower and at one side of two other 75 openings 45. Arranged side by side adjacent to or in contact with the rear face of the back 18 are two gas meters 47 resting on the shelf 27, or, when a shelf is not present, upon some other object. The dials 49 upon 80 the front of these meters register with the openings 44. Electric meters 51 have lateral attaching lugs 52 through which pass screws 53 entering the rear face of the back 18. The dials 55 upon the faces of these electrometers register with the openings 45. The fuse holders 57 are also attached to the back of the panel 18. It will be understood that the number of gas meters or electrometers is immaterial, and that the number of sight 85 openings correspond accordingly.

It is evident that an authorized inspector who is provided with a key fitting the lock of our device may unlock and open the door 23, and note the readings of the meters, and 90 thus not disturb the occupants of the building. The weather lip 20 directs rain and moisture from the casing. The door hinged at its bottom and supported when open exclusively by the chains affords the inspector 100 free use of both hands in making his records.

We claim:—

1. In a building, a wall having an opening therethrough, a frame in said opening, a 105 panel affixed at the rear of said opening and having a sight opening, said panel being non-accessible for removal from the front, said frame having a meter-support extended within the building. 110

2. In a building, a wall having an opening therethrough, a frame in said opening, a panel affixed at the rear of said opening and having a sight opening, said frame being non-accessible for removal from the front, a rearward extension of the frame forming a meter-support within the building, and a hinged door closable within the frame at the front thereof.
5. In a building a wall having an opening therethrough, a frame in said opening, a

panel affixed at the rear of said opening and having a sight opening, said panel being non-accessible for removal from the front, said frame having a door hinged at the 15 lower edge, and door-supporting means connected to the upper part of the door and to the upper part of the frame.

In testimony whereof we have affixed our signatures.

ROCCO C. FAMIGLIETTI.
JOSEPH A. FAMIGLIETTI.
